UNITED STATES PATENT OFFICE.

EARL J. COFFED, OF DEPEW, NEW YORK.

TRESTLE OR SAWHORSE.

Application filed March 30, 1927. Serial No. 179,646.

This invention relates to improvements in foldable trestles or saw horses, such as used by carpenters and other tradesmen, but which may also be conveniently used for supporting benches, tables, platforms and the like.

One of its objects is the provision of a device of this character which can be compactly folded when not in use or for shipping purposes.

Other objects of the invention are to provide a trestle which is strong, durable and inexpensive in construction, and which embodies therein novel means for reliably locking and bracing the legs against accidental collapse during the use of the trestle.

In the accompanying drawings:—

Figure 1 is a sectional side elevation of a saw horse or trestle embodying my improvements. Figure 2 is an end view thereof. Figure 3 is an enlarged sectional perspective view of one end of the trestle. Figure 4 is an enlarged fragmentary vertical longitudinal section taken substantially in the plane of line 4—4, Fig. 2. Figure 5 is an enlarged horizontal section on line 5—5, Fig. 2. Figure 6 is a detail perspective view of the leg-swinging yoke.

Similar characters of reference indicate corresponding parts throughout the several views.

Referring now to the drawings, 10 indicates the platform or rest board of the horse for supporting the scaffolding planks, table or the like, and 11, 11 indicate foldable legs which are disposed at opposite ends of the platform. Each pair of legs is so mounted that it can be swung longitudinally to an unfolded operative position or to a folded position against the platform, and also transversely to extend the legs of a pair to a divergent or bracing position in their unfolded position and to contract them to a substantially parallel position to occupy a space substantially equal to the width of the platform in the folded position thereof. To this end, the legs of a pair are attached to a vertically-swinging yoke or frame 12 fulcrumed on transverse pivot pins 13 carried by depending hangers or plates 14 secured to the opposite sides of the platform. The legs are fulcrumed to this yoke on longitudinal pivot pins 15 by which they may be swung to the divergent or contracted positions shown by full and dotted lines in Fig. 2. The legs may be reliably held in

their divergent operative position by a foldable cross brace consisting of arms 16, 17 pivoted at 18 to the companion legs 11, 11 and to each other at 19. The shorter arm 60 16 terminates at its outer end in a hook or keeper 20 with which the free end of the longer arm 17 is adapted to engage in the extended braced position of the legs, shown by full lines in Fig. 2. Said longer brace-arm 17 is preferably made of angle iron and its horizontal flange acts as a stop which is adapted to abut against the upper edge of the hook 20 and thereby prevent it from swinging below its horizontal locked position.

Secured to the underside of the platform substantially centrally thereof and adjacent each leg-carrying yoke 12 is a depending bracket preferably consisting of a pair of 75 transversely-spaced angle-iron plates 21 riveted or otherwise fastened to the platform. Extending along opposing inner sides of the legs are brace-bars 22, which are connected at one end to the outer sides of 80 the bracket 21 by transverse pivot pins 23, while their opposite ends are attached at 24 to the lower ends of the legs. These brace bars are made of spring steel and their pivots 23 are disposed eccentric to the corresponding pivots 13 of the legs 11, so that upon unfolding the legs to the position shown by full lines in Figs. 1, 2 and 3, their brace-bars will be bowed more or less, as indicated, and thereby tend to hold the legs 90 in a rigid divergent position. Arranged centrally between the brace-bars 22 and pivoted at 25 to the bracket 21 below the pivot pins 23 thereof is a vertically-swinging guide bar or rail 26 which is adapted 95 to move with the legs into and out of their folded position. A substantially U-shaped yoke or slide 27 is capable of movement lengthwise of the guide bar 26 during the folding and unfolding of the legs and is 100 pivotally connected at 28 to one of the arms 29 of a longitudinally-foldable brace, the other arm 30 of the brace being pivoted at 31 to a bracket 32 fastened to the underside 105 of the platform 10. The outwardly-bent flanges 33, 34 of the slide 27 have openings 35 through which the guide bar extends and the outer edge of the latter has a locking notch 36 with which that portion of the upper slide-flange 33 adjacent the outer edge 110 of its opening 35 is adapted to interlock, in the manner shown in Fig. 4. The lower

flange 34 of the slide has a depending lug 37 which is connected to the pivot pin 19 of the foldable cross brace 16, 17, so that as the latter is folded upwardly to contract 5 the legs 11 to the position shown by dotted lines in Fig. 2, the slide will travel upwardly on the guide bar. In the unfolded position of the legs 11, the longitudinally-foldable braces 29, 30 springs the upper end of 10 the slide 27 inwardly to reliably interlock its flange 33 with the notch 36 of the guide bar and thereby prevent displacement of the slide on the latter and accidental collapse 15 of the legs, while the horse is in use.

15 A horizontally-swinging lever or keeper 38 applied to the underside of the platform 10 serves to hold the legs in their collapsed position against said platform, this keeper being arranged to overhang the opposing 20 ends of the foldable braces 29, 30 of both pairs of legs.

I claim as my invention:—

1. A device of the character described, comprising a platform, a pair of foldable 25 legs fulcrumed at each end of the platform to swing both lengthwise and crosswise thereof, said legs when unfolded assuming a downwardly-divergent position, a guide bar fulcrumed at each end of the platform 30 between the companion legs, a slide movable lengthwise of said guide bar, and two sets of foldable braces each having a part thereof connected to said slide, one set of braces holding the legs in their unfolded operative 35 position and the other set holding them in their divergent position.

2. A device of the character described, comprising a platform, a pair of foldable legs fulcrumed at each end of the platform 40 to swing both lengthwise and crosswise thereof, said legs when unfolded assuming a downwardly-divergent position, a guide bar fulcrumed at each end of the platform between the companion legs, a slide movable 45 lengthwise of said guide-bar, a longitudinally foldable brace connected at one end to the platform and at its other end to said slide, and a transversely foldable brace having its ends connected to the legs of a pair, said 50 slide being connected at one end to the transversely foldable brace.

3. A device of the character described, comprising a platform, a pair of foldable legs fulcrumed at each end of the platform 55 to swing both lengthwise and crosswise thereof, said legs when unfolded assuming a downwardly-divergent position, a guide bar fulcrumed at each end of the platform between the companion legs, a slide movable 60 lengthwise of said guide bar, a longitudinally foldable brace connected at one end to the platform and at its other end to said slide, and a transversely foldable brace consisting of pivotally-connected crossed arms 65 attached at their outer ends to the legs of a

pair, said slide being connected to the pivot of said crossed arms.

4. A device of the character described, comprising a platform, a pair of foldable legs fulcrumed at each end of the platform to swing both lengthwise and crosswise thereof, said legs when unfolded assuming a downwardly-divergent position, a guide bar fulcrumed at each end of the platform between the companion legs, a slide movable lengthwise of said guide bar, two sets of foldable braces each having a part thereof connected to said slide, one set of braces holding the legs in their unfolded operative position and the other set holding them in their divergent position, and means for holding said slide against movement on its slide bar in the unfolded position of the legs.

5. A device of the character described, comprising a platform, a pair of foldable legs fulcrumed at each end of the platform to swing both lengthwise and crosswise thereof, said legs when unfolded assuming a downwardly-divergent position, a guide bar fulcrumed at each end of the platform between the companion legs and having a locking notch in one of its edges, a slide movable lengthwise of said guide bar and having a part arranged to engage the locking notch thereof to hold said slide against movement when the legs are unfolded, and two sets of foldable braces each having a part thereof connected to said slide, one set of braces holding the legs in their unfolded position and the other set holding them in their divergent position.

6. A device of the character described, comprising a platform, a pair of foldable legs fulcrumed at each end of the platform to swing lengthwise and crosswise thereof, yieldable brace bars extending along the opposing inner sides of companion legs and each pivoted at one end to the platform between the legs and connected at its other end to the respective leg, said brace bars being free to bow lengthwise and tending to urge the legs to their lateral unfolded position, and a foldable brace for holding the legs in their unfolded position.

7. A device of the character described, comprising a platform, vertically-swinging yokes mounted at each end of the platform, a pair of legs carried by each of said yokes and movable therewith to an unfolded operative position or to a folded inoperative position, said legs being fulcrumed on their yokes to swing relatively thereto and transversely of said platform to assume a downwardly-divergent position when the legs are unfolded, brace bars extending along the opposing sides of companion legs and each pivoted at one end to the platform and connected at its other end to the respective leg, a guide bar fulcrumed at each end of

- the platform between the companion legs, a slide movable lengthwise of said guide bar, a longitudinally foldable brace connected at one end to the platform and at its other end to said slide, and a transversely foldable brace consisting of pivotally-connected, crossed arms attached at their outer ends to the legs of a pair, said slide being connected to the pivot of said crossed arms.
8. A device of the character described, comprising a platform, a pair of foldable legs fulcrumed at each end of the platform to swing lengthwise and crosswise thereof, yieldable brace bars extending along the opposing inner sides of companion legs, each 15 brace bar being pivoted at one end to the platform substantially centrally thereof and eccentric to the leg-fulcrums and connected at its other end to the respective leg, said brace bars being free to bow and tending to 20 urge the legs to their lateral unfolded position, and a foldable brace for holding the legs in their lengthwise unfolded position.

EARL J. COFFED.
